UNITED STATES PATENT OFFICE.

DANIEL S. POST, OF PAINESVILLE, OHIO, ASSIGNOR TO HARRY A. POST,
OF PAINESVILLE, OHIO.

COAL-CHUTE.

SPECIFICATION forming part of Letters Patent No. 789,381, dated May 9, 1905.

Application filed September 6, 1904. Serial No. 223,423.

To all whom it may concern:

Be it known that I, DANIEL S. Post, a citizen of the United States, residing at Painesville, in the county of Lake and State of Ohio, have invented certain new and useful Improvements in Coal-Chutes; and I do declare that the following is a full, clear, and exact description of the invention, which will enable others skilled in the art to which it appertains to make and use the same.

My invention relates to improvements in coal-chutes; and the improvement consists in means for adjustably securing two or more chutes together, substantially as shown and described, and more particularly pointed out in the claims.

The object of this invention is to provide a simple and durable construction which is adapted to adjustably connect two or more chutes together and which comprise means to make one complete chute suitably strengthened to withstand the load and which will not interfere with the passing of the coal or other material through the chute.

In the accompanying drawings, Figure 1 is a perspective view of two sections of my improved coal-chute connected in supporting relation with each other. Fig. 2 is an enlarged perspective view of the larger or connecting end of one of the sections. Fig. 3 is a perspective view in detail of one of the chain-hooks for engaging the side of the chute. Fig. 4 is a side elevation of a portion of two sections in connected relation with the hooks engaging the upper edge of the upper chute.

My invention is used mainly for delivering coal from wagons; but it may be used for other purposes, and usually the two chute-sections A are sufficient; but more sections may be connected together, and the connecting and sustaining portions of the chute must be constructed accordingly with this end in view. Each chute-section is trough-shaped and tapered with the largest width at the upper end. The object in having them tapered is primarily to permit them to be telescoped together for convenience in cartage and also to permit one chute to slide within the other for adjustment.

The upper edge of each side wall 2 of each

section is preferably rounded over and strengthened by a rod 3, running centrally within bead 4 the full length of said sides. A strengthening-band of metal 5 and 6 is secured across the bottom and side of each end 55 of sections A. The reinforcing-band 6 at the upper or larger end of the chute-sections is preferably provided with a depending flange 7 across the bottom of the sections and which has an opening 8 at each side, through which 60 chain 9 is threaded. Hooks 10 at the ends of chain 9 are utilized to engage the upper chute-section either through openings 11 in the sides 2 thereof or clamped to engage over the upper bead 4, as shown in Fig. 4. Chains 9 are 65 of sufficient length to provide a substantially truss connection which is sufficiently strong to hold any two sections together under the weight to be carried. Hooks 10 are preferably constructed of semi-oval material to provide an inner flat face 13, which is adapted to 70 make close engagement with the sides 2 of the chute-sections and having a rounded portion 14 where it enters within the chute to provide the least obstruction to the passing coal. 75

An important advantage over other constructions rests in the free and unobstructed passage for the coal through the chute no matter whether it be small or lump coal and in the further advantage and convenience in adjusting the sections to varying conditions.

What I claim is—

1. In coal-chutes, the combination of trough-shaped sections constructed to telescope one within the other, and chain-and-hook connections secured to the ends of said sections and adapted to secure said sections together. 85

2. In coal-chutes, a section substantially as described comprising a trough member having a reinforcing-band at one end with a depending flange, a chain attached to the end of said sections and hooks for said chain adapted to engage with other sections. 90

3. In coal-chutes, tapering trough-shaped sections provided with reinforcing-bands at 95 the ends thereof, openings in said bands and chains through said openings, and means at the ends of said chains to provide detachable connections with the sides of said trough-shaped sections. 100

4. In coal-chutes, the combination of a plurality of trough-shaped sections constructed to telescope one into the other, the ends of said sections overlapping, and flexible connections engaging the end of the lower section at each side with the sides of the upper section back from its end, substantially as described.

In testimony whereof I sign this specification in the presence of two witnesses.

DANIEL S. POST.
